(57) **CLAIM**

The ornamental design for a sprayer handle, as shown and described.

DESCRIPTION

FIG. 1 is a front top perspective view of a sprayer handle according to a first embodiment of the present design, shown connected to a dispenser of flowable material;

FIG. 2 is a left side view of the sprayer handle of FIG. 1, the right side view being a mirror image of FIG. 2;

FIG. 3 is a top view of the sprayer handle of FIG. 1;

FIG. 4 is a bottom view of the sprayer handle of FIG. 1;

FIG. 5 is a front view of the sprayer handle of FIG. 1;

FIG. 6 is a rear view of the sprayer handle of FIG. 1;

FIG. 7 is a front top perspective view of a sprayer handle according to a second embodiment of the present design, shown connected to a dispenser of flowable material;

FIG. 8 is a left side view of the sprayer handle of FIG. 7, the right side view being a mirror image of FIG. 8;

FIG. 9 is a top view of the sprayer handle of FIG. 7;

FIG. 10 is a bottom view of the sprayer handle of FIG. 7;

FIG. 11 is a front view of the sprayer handle of FIG. 7; and,

FIG. 12 is a rear view of the sprayer handle of FIG. 7.

The broken lines showing the dispenser in FIGS. 1 through 5 and 7 through 12 are for illustrative purposes only and form no part of the claimed design.
